UNITED STATES PATENT OFFICE

2,676,755

DUAL ELECTRONIC COUNTER

Daniel P. Stiff, Fairfield, Ala., assignor to United States Steel Corporation, a corporation of New Jersey

Application November 19, 1952, Serial No. 321,404

4 Claims. (Cl. 235—92)

1

This invention relates to a dual electronic counter and more particularly to such a counter for counting sheets which are to be transferred from a single path to two piles. In certain types of sheet stackers the sheets are discharged from a shearing line onto a narrow dead conveyor on either side of which are conveyors upon which the sheets are stacked by hand. Operators stand on each side of the dead conveyor and each sheet is pulled toward one or the other of the operators and placed on a pile. It is desired to count the number of the sheets in each pile.

It is therefore an object of my invention to provide a dual electronic counter by which sheets are removed transversely from their path of travel, piled in stacks on each side of the path of travel with the sheets in each pile being automatically counted.

These and other objects will be more apparent after referring to the following specification and attached drawings, in which:

Figure 1 is a plan view of the apparatus with which the counter is associated;

Figure 2 is a side elevation of the apparatus of Figure 1;

Figure 3 is an enlarged plan view, showing part of the apparatus of Figure 1, with the position of the counter being indicated; and

Figure 4 is a schematic wiring diagram of the counter.

Referring more particularly to Figures 1, 2 and 3 of the drawings, sheets S traveling over a conveyor 2 are delivered to a narrow dead roller conveyor 4, commonly called a mill bar. Mounted below the mill bar 4 on each side thereof are roller conveyors 6 and 8. An operator stands at the side of each of the conveyors 6 and 8 and alternately removes sheets S from the mill bar 4. Located above the mill bar 4 is a light source 10 beneath which are mounted a pair of phototubes 12 and 14. It will be noted that the phototubes 12 and 14 are mounted side by side transversely of the mill bar 4. The phototubes 12 and 14 are connected to a control unit 16 which operates the counters 18 and 20. The counters 18 and 20 may be of a standard electromagnetic type.

Referring to Figure 4, power for the photocells 12 and 14 and control unit 16 is provided from 110 volt A. C. power lines 22 and 24. The lines 22 and 24 supply power to the primaries of transformers 26 and 28, the secondaries of which are connected to rectifier tubes 30 and 32, respectively. The cathodes of the tubes 30 and 32 are connected to filters 34 and 36, respectively. The

filter 34 consists of a transformer 38 and two condensers 40 connected to ground. The filter 36 consists of a similar transformer 42 and condensers 44 connected to ground. Alternating current for the circuit is taken from the secondary of transformer 26 by means of the wire 46. The other side of the alternating current is connected to ground. A positive direct current is taken from the filter 34 by means of the wire 48. A negative direct current is taken from the filter 36 by means of the wire 50. The other side of the direct current is connected to ground. Other means than those described above may be used as the source of power. The wire 50 is connected to the cathodes of the phototubes 12 and 14 through a voltage divider consisting of resistors 52 and 54 which insures that the right potential is provided to the cathodes. Two electronic tubes 56 and 58 have their grids 56G and 58G connected to the anode of phototube 12. The cathodes 56C and 58C are connected to ground and the cathode 56C is connected to grid 58G through a resistor 60. Two electronic tubes 62 and 64 have their grids 62G and 64G connected to the anode of phototube 14. The cathodes 62C and 64C are connected to ground. The cathode 64C is connected to the grid 64G through resistor 66. A thyratron tube 68 has its grid 68G connected to the plate 56P through resistors 70 and 72. The resistor 70 is connected to the wire 50 in series with a resistor 74 and to ground through a resistor 76. The plate 68P is connected to the wire 46 through the primary of a transformer 78. A second thyratron tube 80 has its grid 80G connected to the plate 62P through resistors 82 and 84. Resistor 82 is connected to the line 50 in series with a resistor 86 and to ground in series with a resistor 88. The plate 80P is connected in parallel with the plate 68P to the line 46 through the primary of a transformer 88. The cathodes 68C and 80C are connected to ground through a resistor 91.

Dual vacuum tubes 92 and 94 are connected as a "flip-flop" or "trigger" type multivibrator circuit. The grids 92G and 94G are connected in parallel to the wire 50 through resistors 96 and 98, respectively, and to ground through resistors 100 and 102, respectively. The plate 64P is connected to grid 92G through resistor 104 and to plate 62P through resistors 106 and 108 connected in series. Plate 62P is connected to the plate 58P through resistors 108 and 110. Cathodes 92C and 94C are connected in parallel to ground through resistor 112. Plates 92P and 94P are connected in parallel through resistors

114 and 116 to the wire 48. Plate 92P is connected to grid 94G through resistor 118.

Flow of current through counters 13 and 20 is controlled by means of thyratron tubes 128 and 122, respectively, the counters being connected to the plates 128P and 122P. The plates 120P and 122P are also connected to the wire 22 through capacitors 124 and 126, respectively. The cathode 120C is connected to the wire 50 through resistors 128 and 130 connected in series. The cathode 122C is connected to the wire 50 through resistors 128 and 130 connected in series. The grids 120G and 122G are connected in parallel to plate 94P through capacitors 136 and 138, respectively. The grid 120G is connected to the plate 140P of vacuum tube 149 through resistor 142. The grid 140G is connected to wire 50 through resistors 128 and 144. One side of the secondary of transformer 78 is connected to the cathode 140C and the other side is connected to the grid 140G through resistor 144. The grid 122G is connected to the plate 146P of a vacuum tube 146 through resistor 148. The grid 146G is connected to wire 50 through resistors 132 and 150. One side of the secondary of transformer 90 is connected to the cathode 146C and the other side of the grid 146G through resistor 150.

The operation of the counters is as follows:

Assuming that there is light on the photocells 12 and 14 the resistance will be low and there will be negative voltage on the grids of tubes 58, 59, 62 and 64. The grids of these tubes will be most negative so that the tubes are biased beyond cut-off and will not conduct. Since tubes 58 and 64 are not conducting their plate voltage is high, thus causing the grid bias voltage of tube 92 to be slightly positive so that it will conduct. Since tubes 92 and 94 are connected as a "flip-flop" multivibrator circuit the tube 94 will be cut off. The connections of thyratron tubes 68 and 80 are such that if one tube fires or conducts the other cannot. Assuming that the tube 68 is conducting there will be current flowing through the primary of transformer 78 and the voltage of the secondary of the transformer will be rectified by the tube 140 and introduced into the grid 120G of tube 120 as a high negative voltage so that tube 120 cannot conduct. Under the foregoing conditions the grids of tubes 120 and 122 are biased from line 50 so that they are not conducting.

When a sheet is delivered to the mill bar 4 over the photocells 12 and 14, light to the photocells 12 and 14 will be cut off and the tubes 58, 59, 62 and 64 will all conduct. The plate voltage of the tubes 58 and 64 is low due to the drop in their common plate load resistor 106 and the bias on tube 92 will be negative, thus causing tube 92 to be cut off and tube 94 to conduct. The plate voltage of tubes 58 and 62 is low which causes the tubes 68 and 80 to be biased beyond cut off and no voltage is developed in the secondary of transformers 78 and 90. Therefore, tubes 120 and 122 will be biased beyond cut off. When tube 94 started to conduct a negative pulse was transmitted to the grids of tubes 120 and 122 but without causing any change in their operation.

Assuming that the sheet S is to be removed to conveyor 8 the photocell 12 will be uncovered while photocell 14 remains covered. Under these conditions the tube 58 will be cut off thus causing a high positive voltage to be impressed on plate 56P which is transmitted through resistor 72 to grid 68G thus causing tube 68 to fire. The grid bias on the thyratron tube 68 is slightly positive when there is no light on the photocell. This

tends to keep the gas ionized even though the plate potential is negative. The transformer 78 in the plate circuit of tube 68 contains considerable inductance. This inductance and the fact that the grid is slightly positive tends to keep the current flowing during the negative cycle of the plate potential. This produces a voltage in the secondary of transformer 78 which is rectified by tube 140 and is developed across resistor 144. This produces a high negative voltage which is applied to the grid 120G. Tube 58 is cut off at the same time tube 56 is cut off, but the plate voltage of tube 58 does not change appreciably due to its common plate load resistor 106 and since tube 64 is still conducting the voltage across resistor 106 does not change enough to cause tube 92 to conduct. Therefore, tube 94 is still conducting and tube 92 cut off and no pulse is transmitted to the grids of tubes 120 and 122.

Removal of the sheet S to the conveyor 8 uncovers the photocell 14 and the tube 92 is cut off with no effect since tube 80 is locked out by tube 68. Tube 64 is cut off and its plate voltage is raised causing tube 92 to conduct and tube 94 to be cut off. When tube 94 is cut it transmits a sharp positive pulse to the grids of tubes 120 and 122 through the coupling condensers 136 and 138. This has no effect on tube 120 since the voltage rectified by tube 140 has a greater negative value than the positive pulse can overcome. However, the pulse is sufficient to overcome the grid bias of tube 122 causing it to conduct momentarily and operate the counter 20. The circuit is now ready to receive another sheet S which will cover both phototubes with the same result as above.

Assuming that the second sheet is to be pulled off in the opposite direction so that phototube 14 is uncovered first, the tube 64 will be cut off with no effect and tube 62 will be cut off raising its plate voltage and causing tube 80 to fire. The voltage developed in the secondary of plate transformer 90 is rectified by tube 146 and introduced as a high negative voltage across resistor 150 to the grid circuit of tube 122. Therefore, tube 122 will not be able to fire even with a positive pulse from tube 94. Tube 92 will be cut off and tube 94 will be conducting.

When a sheet is removed completely from the mill bar 4 there will be light on both phototubes and the positive voltage of tube 58 will be raised causing the "flip-flop" of tubes 92 and 94 to send a positive pulse to the grids of tubes 120 and 122. This pulse has no effect on tube 122 but will cause tube 120 to conduct and operate the counter 13.

The above operations will be repeated each time a sheet is received over the photocells 12 and 14 and removed in one direction or the other.

While one embodiment of my invention has been shown and described it will be apparent that other adaptations and modifications may be made without departing from the scope of the following claims.

I claim:

1. In apparatus wherein traveling sheets or the like are removed transversely from their path of travel in two directions, a pair of counters for separately and automatically counting the sheets removed in each direction, a pair of photocells arranged transversely of the path of travel of said sheets on one side of said sheets, a light source on the other side of said sheets, a first thyratron tube, a second thyratron tube, one of 70 said counters being in the plate circuit of the 75 said counters being in the plate circuit of the

first thyratron tube and the other of said counters being in the plate circuit of the second thyratron tube, a first and second tube each having its grid connected to the anode of the first of said photocells, said first and second tubes being adapted to fire only when light is not on the first photocell, a third and fourth tube each having its grid connected to the anode of the second of said photocells, said third and fourth tubes being adapted to fire only when light is not on the second photocell, means connected to said four tubes for providing a high negative voltage on the grid of the second thyratron tube when a sheet covering both photocells is removed from the second photocell, means connected to said four tubes for providing a high negative voltage on the grid of the first thyratron tube when a sheet covering both photocells is removed from the first photocell, and means responsive to the uncovering of the remaining photocell for applying a positive pulse on the grids of the thyratron tubes whereby the tube without the negative pulse thereon will conduct and the other tube will not.

2. In apparatus wherein traveling sheets or the like are removed transversely from their path of travel in two directions, a pair of counters for separately and automatically counting the sheets removed in each direction, a pair of photocells arranged transversely of the path of travel of said sheets on one side of said sheets, a light source on the other side of said sheets, a first thyratron tube, a second thyratron tube, one of said counters being in the plate circuit of the first thyratron tube and the other of said counters being in the plate circuit of the second thyratron tube, a first and second tube each having its grid connected to the anode of the first of said photocells, said first and second tubes being adapted to fire only when light is not on the first photocell, a third and fourth tube each having its grid connected to the anode of the second of said photocells, said third and fourth tubes being adapted to fire only when light is not on the second photocell, means connected to said four tubes for providing a high negative voltage on the grid of the second thyratron tube when a sheet covering both photocells is removed from the second photocell, means connected to said four tubes for providing a high negative voltage on the grid of the first thyratron tube when a sheet covering both photocells is removed from the first photocell, and a flip-flop circuit connected to said four tubes responsive to the uncovering of the remaining photocell for applying a positive pulse on the grids of the thyratron tubes whereby the tube without the negative pulse thereon will conduct and the other tube will not.

3. In apparatus wherein traveling sheets or the like are removed transversely from their path of travel in two directions, a pair of counters for separately and automatically counting the sheets removed in each direction, a pair of photocells arranged transversely of the path of travel of said sheets on one side of said sheets, a light source on the other side of said sheets, a first and second tube each having its grid connected to the anode of the first of said photocells, said first and second tubes being adapted to fire only when light is not on the first photocell, a third and fourth tube each having its grid connected to the anode of the second of said photocells, said third and fourth tubes being adapted to fire only when light is not on the second photocell, electrical connections between the plates of said tubes, a first thyratron tube, an electrical connection between the plate of the first tube and the grid of the first thyratron tube, a second thyratron tube, said thyratron tubes being cut off when the first four tubes are conducting, the first thyratron tube starting to fire when the first and second tubes are cut off and the third and fourth tubes are firing, the second thyratron tube starting to fire when the third and fourth tubes are cut off and the first and second tubes are firing, an electrical connection between the plate of the third tube and the grid of the second thyratron tube, an electrical connection between the cathodes of said thyratron tubes, a first transformer having its primary in the plate circuit of the first thyratron tube, a second transformer having its pri-

nction between the plate of the first tube and the grid of the first thyratron tube, said thyratron tubes being cut off when the first four tubes are conducting, the first thyratron tube starting to fire when the first and second tubes are cut off and the third and fourth tubes are firing, the second thyratron tube starting to fire when the third and fourth tubes are cut off and the first and second tubes are firing, an electrical connection between the plate of the third tube and the grid of the second thyratron tube, an electrical connection between the cathodes of said thyratron tubes, a first transformer having its primary in the plate circuit of the first thyratron tube, a second transformer having its primary in the plate circuit of the second thyratron tube, a fifth tube having its cathode connected to one side of the secondary of the first transformer, a sixth tube having its cathode connected to one side of the secondary of the second transformer, a third thyratron tube having its cathode connected to the other side of the secondary of the first transformer, said third thyratron tube having a high negative voltage applied to its grid when current flows through the first transformer, a fourth thyratron tube having its cathode connected to the other side of the secondary of the second transformer, said fourth thyratron tube having a high negative voltage applied to its grid when current flows through the second transformer, an electrical connection between the plate of the fifth tube and grid of the third thyratron tube, an electrical connection between the plate of the sixth tube and grid of the fourth thyratron tube, one of said counters being in the plate circuit of each of said third and fourth thyratron tubes, and means responsive to the successive uncovering of the photocells for applying a positive pulse on the grids of the third and fourth thyratron tubes whereby the tube without the negative pulse thereon will conduct and the other tube will not.

4. In apparatus wherein traveling sheets or the like are removed transversely from their path of travel in two directions, a pair of counters for separately and automatically counting the sheets removed in each direction, a pair of photocells arranged transversely of the path of travel of said sheets on one side of said sheets, a light source on the other side of said sheets, a first and second tube each having its grid connected to the anode of the first of said photocells, said first and second tubes being adapted to fire only when light is not on the first photocell, a third and fourth tube each having its grid connected to the anode of the second of said photocells, said third and fourth tubes being adapted to fire only when light is not on the second photocell, electrical connections between the plates of said tubes, a first thyratron tube, an electrical connection between the plate of the first tube and the grid of the first thyratron tube, a second thyratron tube, said thyratron tubes being cut off when the first four tubes are conducting, the first thyratron tube starting to fire when the first and second tubes are cut off and the third and fourth tubes are firing, the second thyratron tube starting to fire when the third and fourth tubes are cut off and the first and second tubes are firing, an electrical connection between the plate of the third tube and the grid of the second thyratron tube, an electrical connection between the cathodes of said thyratron tubes, a first transformer having its primary in the plate circuit of the first thyratron tube, a second transformer having its pri-

mary in the plate circuit of the second thyratron tube, a fifth tube having its cathode connected to one side of the secondary of the first transformer, a sixth tube having its cathode connected to one side of the secondary of the second transformer, a third thyratron tube having its cathode connected to the other side of the secondary of the first transformer, said third thyratron tube having a high negative voltage applied to its grid when current flows through the first transformer, a fourth thyratron tube having its cathode connected to the other side of the secondary of the second transformer, said fourth thyratron tube having a high negative voltage applied to its grid when current flows through the second transformer, an electrical connection between the plate of the fifth tube and grid of the third thyratron tube, an electrical connection between the plate of the sixth tube and grid of the fourth thyratron tube, one of said counters being in the plate circuit of each of said third and fourth thyratron tubes, a flip-flop circuit comprising a seventh and an eighth tube, an electrical connection between the plate of the seventh tube and

grid of the eighth tube, an electrical connection between the grid of the seventh tube and plate of the fourth tube, an electrical connection including a capacitor between the plate of the eighth tube and grid of the third thyratron tube, and an electrical connection including a capacitor between the plate of the eighth tube and grid of the fourth thyratron tube, said eighth tube being adapted to fire when the first four tubes are conducting and to be cut off when the first four tubes are cut off, said fourth thyratron tube firing when said eighth tube is cut off and said first thyratron tube is firing, said third thyratron tube firing when said seventh tube is cut off and said second thyratron tube is firing.
